UNITED STATES PATENT OFFICE

117,831

DESIGN FOR A COMBINED RUBBER SOLE
AND HEEL

Francis A. Johnson, Endicott, N. Y., assignor to
Endicott Johnson Corporation, Endicott, N. Y.,
a corporation of New York

Application March 28, 1939, Serial No. 83,885

Term of patent 14 years

To all whom it may concern:

Be it known that I, Francis A. Johnson, a citizen of the United States, residing at Endicott, county of Broome, State of New York, and whose post-office address is 1106 Broad Street, in said village, have invented a new, original, and ornamental Design for a Combined Rubber Sole and Heel, of which the following is a specification, reference being had to the accompanying drawing, constituting a part thereof.

In said drawing:

Fig. 1 is a bottom plan view of a combined rubber sole and heel showing my new design.

Fig. 2 is an enlarged transverse section on the line 2—2, Fig. 1.

Fig. 3 is a top perspective view thereof.

The characteristic features of the combined rubber sole and heel are the tapered upper surface of the shank connecting the upper surface of the heel portion with the upper surface of the relatively thinner sole portion; also the provision on the entire area of the flat tread portions of the sole, heel, and shank of uniformly spaced narrow intersecting ribs of substantial height and constant cross-section forming relatively deep recesses of parallelogrammatic shape having parallel side walls.

I claim:

The ornamental design for a combined rubber sole and heel, substantially as shown and described.

FRANCIS A. JOHNSON.
